UNITED STATES PATENT OFFICE

JAMES C. BENNETT, OF DETROIT, MICHIGAN

SOOT BLOWER FOR BOILERS

Application filed December 17, 1924. Serial No. 756,452.

This invention relates to soot blowers for boilers of that type utilizing steam as an agent for removing soot, incrustations and foreign matter from the exterior surfaces of boiler tubes, to increase the efficiency of the boiler as a steam generating apparatus.

One of the objects of the invention is to provide a device of this character wherein a rotary blower arm when turned in one direction causes opening of a steam supply valve, and when turned in the opposite direction causes the closing of said valve.

Another object of this invention is to furnish a rotary blower arm with a steam control valve and means for opening and closing the valve during partial rotation of the blower arm.

A further object of this invention is to furnish a blower arm with steam supply connections or fittings that will permit of the arm receiving steam during a rocking movement of the arm, and provision is made for regulating the degree of arm rocking so that steam ejected from the arm may be directed towards adjacent boiler tubes.

A still further object of this invention is to provide a soot blowing apparatus wherein a blower arm and steam connections or fittings are supported in a manner, as to be hereinafter described, that precludes stresses and strains on the connections that might cause leakage of steam during the operation of the apparatus.

The above and other objects are attained by a durable and inexpensive structure that will be hereinafter specifically described and then claimed, and reference will now be had to the drawings, wherein

Figure 1 is a longitudinal sectional view 40 of a soot blowing apparatus in accordance with this invention;

Fig. 2 is a cross sectional view taken on the line II—II, Fig. 1;

Fig. 3 is a similar view taken on the line 45 III—III, Fig. 1;

Fig. 4 is a plan of the soot blowing apparatus partly in section;

Fig. 5 is a cross sectional view taken on the line V—V of Fig. 1;

Fig. 6 is a longitudinal sectional view of

a steam valve adapted to form part of the apparatus, and

Fig. 7 is a cross sectional view taken on the line VII—VII of Fig. 1.

In the drawings the reference numeral 1 denotes a boiler setting, wall or other support that is in proximity to boiler tubes 2 adapted to have soot and incrustations removed therefrom by steam or a like agent forcibly projected against or towards the tubes.

Mounted in the setting 1 is a tubular member 3 having diagrammatically opposed ears 4 to which are connected, by nut equipped bolts 5 the upstanding ears 6 of a horizontally disposed yoke shaped support 7, which has opposed ends provided with sleeve connections 8 and 9.

In these sleeve connections are mounted the lateral connections 10 and 11 of a valve body 12, and connected to the connections 9 and 10 is a steam supply pipe 13. Extending through the connection 8 and attached to the valve body connection 11 is a steam outlet coupling member 14 to which is connected, as at 15, a goose neck 16 of a stuffing box 17 located above the valve body 12, said stuffing box and its goose neck cooperating with the outlet coupling member 14 in forming a steam connection or fitting.

The stuffing box 17 has a conventional form of gland 18 and packing 19 for the inner end of a blower arm 20 which extends through the tubular member 3 into proximity to the tubes 2. The blower arm is preferably in the form of a pipe or conduit provided with a plurality of steam discharging nozzles 21, of the internal type, said nozzles being arranged so that the outer end of the blower arm constitutes a large nozzle for distributing and directing steam towards and against the tubes 2.

The blower arm 20 is rotatable in the stuffing box 17 and a closure 22 loosely fitted on the blower arm against the tubular member 3. Fixed on the blower arm 20 against the closure 22 is the hub portion 23 of a large sprocket wheel 24, and mounted on the hub 23 is a coiled expansion spring 25 having one convolution fixed in the hub 23 and another 100

convolution bearing against the closure 22 to hold it against the end of the tubular member 3 to close said member.

Suitably attached to the sprocket wheel 24, preferably by nut equipped bolts 26, is a sector gear or rack 27 meshing with a sector gear or pinion 28 mounted on a valve stem 29. This valve stem extends through a stuffing box or bonnet 30 of the valve body 12 and is provided with a one-way conical plug 31 within the valve body 12. The plug 31 controls the passage of steam through the valve and said plug is properly adjusted within the valve body 12 and under the influence of the expandable force of a spring 32 to prevent the plug from sticking in the valve body; there being rotation of the valve plug without leakage of steam and without any danger of the valve becoming inoperative because of expansion of valve parts incident to steam passing through the valve.

Connected to the support 7 is a U-shaped bracket 33 having an end thereof provided with a bearing 34 for the valve stem 29. On the bracket 33, at that side of the sprocket wheel 24 opposite the sector gear or pinion 28 is a stop member or abutment 35 adapted to be engaged by stop pins 36 and 37 adjustably connected to the sprocket wheel 24, said wheel having a series of openings 38 in which the stop pins may be set so that said pins will control the degree of rotation of said sprocket wheel by a sprocket chain 39 or its equivalent employed for imparting rotation or oscillation to the blower arm 20.

Assuming that the soot blowing apparatus is in the position as shown in the drawings, with the steam supplying valve closed it is desired to admit steam to the blower arm 20, the sprocket wheel 24 is rotated in a clockwise direction, considering Fig. 5 or in a counter-clockwise direction considering Fig. 1. Such rotation of the sprocket wheel moves the pin 36 away from the abutment 35 and the rotation may be continued until the pin 37 engages the abutment 35. Initial rotation of the sprocket wheel 24 causes the sector gear 27 to rotate the sector gear or rack 28 and open the valve so that steam may pass there-through into the steam connection or fitting and into the blower arm 20. The subsequent rotation of the sprocket wheel 24 carries the sector gear 27 out of engagement with the pinion 28 and the sector gear 27 is carried around by the sprocket wheel 24 until such time as the pin 37 engages the abutment 35. On reversal of the sprocket wheel the sector gear 27 is again brought into mesh with the pinion 28 in the position where it was last released, or open position, to close the valve. It will therefore be seen that during partial rotation of the blower arm 20 the steam supply valve is opened and that reverse movement closes the valve, the closing being completed when the pin 36 engages the abutment 35.

The valve plug 31 is adapted to be oscillated for turning off and on the valve, but the oscillation of the valve plug is intermittent relative to a complete oscillation of the sprocket wheel, and it is by virtue of the adjustable pins 36 and 37 that the degree of oscillation imparted to the blower arm may be regulated so that the blower arm will discharge steam in desired directions according to the location of the boiler tubes 2.

The automatic control of the steam supply valve, during oscillation of the blower arm, obviates manual control of such a valve, and while I have herein shown a two-way plug valve, it is to be noted that this valve differs in construction from an ordinary valve of such type for the reason that the plug and valve body are devoid of stops, because the stops are associated with other elements of my device. It is to be understood that other engageable and disengageable valve operating means may be associated with the blower arm for automatically opening and closing the steam supply valve, and such other changes may be made as are permissible by the appended claims.

What I claim is:—

1. In a soot blower, a rotary blower arm having a lateral outlet, means for supplying steam to said arm, a valve in said means, a gear segment movable with said arm, a pinion carried by said valve and engageable by said segment, means for turning said arm alternately in opposite directions, said gear segment being arranged to open the valve in one direction of turning and to close the valve in the other direction of turning, and b-terminal stop means for said arm and gear operative on disengagement of said gear from said pinion in either direction of turning.

2. In a soot blower, a rotary blower arm having a lateral outlet, means for supplying steam to said arm, a valve in said means, a gear segment movable with said arm, a pinion carried by said valve and engageable by said segment, means for turning said arm alternately in opposite directions, said gear segment being arranged to open the valve in one direction of turning and to close the valve in the other direction of turning, a fixed stop abutment, and a carrier member rotatable with said arm, stop pins carried by said member and engageable respectively with opposite sides of said abutment to limit the turning movement of said arm in both directions, said pins being located to engage said abutment on disengagement of said gear from said pinion in either direction of turning.

3. In a soot blower, a rotary blower arm having a lateral outlet, means for supplying steam to said arm, a valve in said means, a gear segment movable with said arm, a pinion carried by said valve and engageable by said segment, means for turning said arm al-

ternately in opposite directions, said gear segment being arranged to open the valve in one direction of turning and to close the valve in the other direction of turning, a fixed stop 5 abutment, and a carrier member rotatable with said arm, stop pins carried by said member and engageable respectively with opposite sides of said abutment to limit the turning movement of said arm in both directions, said 10 pins being located to engage said abutment on disengagement of said gear from said pinion in either direction of turning, said pins being adjustable on said carrier member circularly around said arm.

15 In testimony whereof I affix my signature.
JAMES C. BENNETT.
